ATTORNEY

UNITED STATES PATENT OFFICE.

ROBERT J. JAMES, OF SEATTLE, WASHINGTON.

SPECTACLES.

1,275,933.

Specification of Letters Patent. Patented Aug. 13, 1918.

Application filed October 15, 1917. Serial No. 196,758.

To all whom it may concern:

Be it known that I, ROBERT J. JAMES, a citizen of the United States, residing at Seattle, in the county of King and State of Washington, have invented certain new and useful Improvements in Spectacles, of which the following is a specification.

This invention relates to improvements in spectacles and more particularly in spectacles which are designed for the use of physicians and the like and has for its principal object to provide an improved and novel means for supporting the spectacles with respect to the person. Another object 10 of my invention is to provide an improved construction in spectacles whereby they may be supported from the cranium and face with three different points of support. In spectacles as used by physicians and the like 15 when performing an important operation it is important that they be held securely in place and that they do not become loosened as is quite usual with the usual type of nose 20 mountings. The spectacle which is held by 25 hooking over the ears is very annoying and quite objectionable to many people. My mounting is designed to obviate the above 30 objections and to provide means whereby the glasses may be supported entirely by resting 35 upon the nose and from gripping the cranium of the wearer.

Other objects will appear as my invention 40 is more fully explained in the following specification, illustrated in the accompanying 45 drawings and pointed out in the appended claims.

In the drawings Figure 1 is a front elevation 50 of my device shown in closed position. Fig. 2 is an enlarged fragmentary end elevation of same with the holding means shown 55 in open position. Fig. 3 is a plan of Fig. 2.

Referring more particularly to the drawing 60 numeral 1 indicates the usual spectacle bows which are separated by a nose piece 2. 45 My improvements includes relatively short clamp arms 3 which are hinged to levers 4 which in turn are secured by means of pivot pins 5 to the outer ends of bows 1. The levers 4 are provided with up-turned thumb 65 catches 4^a on their free ends and are normally held in the position shown in Fig. 1 by means of small coil springs 6. The object of 70 the hinging together of the lever 4 and the

clamp arm 3 is for the purpose of facilitating a neat and compact folding of the device 55 and at the same time permitting the thumb catches to extend far enough away from the line of the bow in order to permit of the device being easily opened. The outer ends of the clamp arms 3 are provided with 60 rounded and flattened grips 3^a which are designed to grip the cranium without irritation. In using my device the levers and clamp arms are thrown outwardly with the thumb and finger as is usual in nose piece 65 glass mountings. The nose piece 2 is then placed upon the nose as usual and the levers released with respect to the clamp arms engaging the cranium of the wearer about the point of the temple thereby gripping either 70 side of his head and securely holding the spectacles from dropping from the nose. It will be understood that the clamp arms grip the sides of the head with sufficient 75 force to prevent accidental removal and not hard enough to injure or annoy the wearer.

While I have shown a particular form of embodiment of my invention, I am aware that many minor changes therein will readily suggest themselves to others skilled in 80 the art without departing from the spirit and scope of the invention, and I therefore desire to avoid being limited to the exact form shown and described.

Having described my invention, what I 85 claim as new and desire to protect by Letters Patent, is:—

1. In a device of the class described the combination of a pair of spectacle bows connected together by a nose piece, a pair of 90 similar levers, pivot pins pivotally connecting the said levers intermediate their ends to the extreme ends of the said bows, clamp arms pivotally connected to the inner ends of the said levers and having a limited 95 movement with respect thereto, coil springs wrapped around the said pivot pins and hooked over the outer ends of the said levers, whereby the levers and clamp arms are swung inwardly, up-turned thumb catches 100 on the outer ends of the said levers, whereby the levers and clamp arms may be moved without taking hold of the bows.

2. The combination with a pair of spectacle bows, of a pair of similar levers each 105 pivoted midway its length to one end of the

said bows, clamp arms pivotally connected to the inner ends of the said levers and having a limited movement with respect to the said levers, up-turned thumb catches on the outer ends of the said levers, whereby the levers and clamp arms may be actuated, and coil springs mounted in the hinge point of the levers and bows and hooked over the said

levers, whereby the inner ends of the said levers are normally thrown inwardly.

10

In testimony whereof I affix my signature in the presence of two witnesses.

ROBT. J. JAMES.
